(57) **CLAIM**

The ornamental design for a bottle, as shown and described.

DESCRIPTION

FIG. 1 is a front and top perspective view of a bottle, shown without the bottle body, showing my new design; FIG. 2 is a rear and bottom perspective view thereof, shown without the bottle body;

FIG. 3 is a front elevation view thereof, shown without the bottle body;

FIG. 4 is a rear elevation view thereof, shown without the bottle body;

FIG. 5 is a left side elevation view thereof, shown without the bottle body;

FIG. 6 is a right side elevation view thereof, shown without the bottle body;

FIG. 7 is a top plan view thereof, shown without the bottle body;

FIG. 8 is a bottom plan view thereof, shown without the bottle body;

FIG. 9 is a front and top perspective view of the bottle, shown without the bottle liner;

FIG. 10 is a rear and bottom perspective view thereof, shown without the bottle liner;

FIG. 11 is a front elevation view thereof, shown without the bottle liner;

FIG. 12 is a top plan view thereof, shown without the bottle liner;

FIG. 13 is a bottom plan view thereof, shown without the bottle liner;

FIG. 14 is a front and top perspective view of the bottle, shown in a fully assembled configuration;

FIG. 15 is a rear and bottom perspective view thereof, shown in a fully assembled configuration;

FIG. 16 is a front elevation view thereof, shown in a fully assembled configuration;

FIG. 17 is a left side elevation view thereof, shown in a fully assembled configuration;

FIG. 18 is a top plan view thereof, shown in a fully assembled configuration; and,

(Continued)

FIG. 19 is a bottom plan view thereof, shown in a fully assembled configuration. The broken lines in the figures illustrate portions of the bottle that form no part of the claimed design.
